Whole No. 1396

A. G. Barstow, of Providence, R. I., Letters Patent No. 31, dated Mar. 26, 1861.

The schedule referred to in these Letters Patent and making part of the same Schedule to whom these Presents shall come.

Be it known that I, A. G. Barstow, of Providence, in the County of Providence, and State of Rhode Island, have invented a new and useful design for "Base for Parlor Stove," and I do hereby declare that the following description taken in connection with the accompanying drawings, to which reference is hereinafter made, is a full and exact description of the said design.

The figures of the accompanying plate of drawings represent my new design.

Fig. 1. is a plan or top view.

Fig: 2. is a side view of ... same.

Fig: 3. is a horizontal section taken in the plane of the lines 4:5

Fig: 4. is a transverse vertical section taken in plane of the line 6.D. fig: 1. a. a. in the drawings represent the bottom plate of the base of the general curved outline shown and ornamented with figures b.b. On the bottom plate
a. a. rests a superstructure c.c. of the ornamental curved form shown, and having on its exterior a series of shields d.d. ornamented with raised figures e.e.
Upon this superstructure c.c. rests a plate f.f. of the same general form as the superstructure c.c. and ornamented with raised leaves g.g.

Having thus described my new design, I shall state my claim as follows:

What I claim as my invention and desire to have secured to me by Letters Patent, is the new design for Base for Parlor Stoves, having the general ornamental form and configurations as herein above described and represented in the drawings.

Witnessed.

George Richmond,
William F. Elliot.
